UNITED STATES PATENT OFFICE.

JULIUS HABITZREITER, OF CHICAGO, ILLINOIS.

NEWSPAPER-FILE.

SPECIFICATION forming part of Letters Patent No. 340,305, dated April 20, 1886.

Application filed June 5, 1885. Serial No. 167,726. (No model.)

To all whom it may concern:

Be it known that I, JULIUS HABITZREITER, of Chicago, in the county of Cook and State of Illinois, have invented certain new and useful Improvements in Newspaper-Files, of which the following is a specification.

This invention has reference to an improved newspaper-holder for conveniently filing and handling newspapers; and the invention consists of a newspaper-holder the main bar or stock of which is made of two parallel wires, that are attached to a handle and retained by metallic clasps, and of a spring-wire that is hinged to lugs of the end clasp and locked at its lower hook-shaped end between a fixed stud of the clasp next to the handle and a movable cheek operated by a fastening screw passing through the fixed cheek.

In the accompanying drawings, Figure 1 represents a front elevation, Fig. 2 a side elevation, and Fig. 3 a rear elevation, of my improved newspaper-holder; and Figs. 4 and 5 are horizontal sections, respectively on lines *x x*, Fig. 1, and *y y*, Fig. 3.

Similar letters of reference indicate corresponding parts.

In the drawings, A represents the stock or main bar of my improved newspaper-holder, which bar is formed of two stout wires, *a a*, which are retained sidewise of each other by means of cast-metal clasps *a' a' a'*, of which preferably three are arranged that unite the wires *a a*, respectively, at the ends and at an intermediate point, as shown in Figs. 1, 2, and 3. The clasps *a' a' a'* extend across the back and over the sides of the wires *a*, but not across the front of the same, so as to leave a space for the clamping spring-wire B, which is hinged by an eye at its outer end to lugs *b* of the outer clasp, *a'*, and which serves to hold the newspaper in the groove formed between the wires *a a*. The lower end of the spring-wire B is bent into semicircular or hook shape and rigidly clamped between a fixed

cheek, *d*, made integral with the lowermost clasp, *a'*, which is located next to the handle C, and a movable cheek, *d'*, that is applied by a thumb-screw, *d'*, to the bent end of the spring-wire B, so as to be locked into position close to the main bar A when the lower end is pressed by the thumb between the fixed and movable cheeks *d d'*.

By loosening the thumb-screw *d'* the spring-wire B is released, so that it springs away from the main bar A and permits thereby the ready insertion or removal of the newspaper. The clasp *a'*, at the outer end of the main bar A, is further provided with a sidewise-projecting hook, *f*, that is cast integral therewith, so that the holder can be conveniently suspended from a hook or other suitable point of support on the wall.

Having thus described my invention, I claim as new and desire to secure by Letters Patent—

1. The combination of a main bar formed of two wires and metallic retaining-clasps, a clamping spring-wire hinged to the outermost clasp, and a clamping device, substantially as described, for locking or releasing the inner end of the spring-wire to or from the lower clasp, substantially as set forth.

2. The combination of the supporting main bar formed of two wires and metallic retaining-clasps, a clamping spring-wire hinged to the outer clasp, said spring-wire having a bent lower end, and a clamping device formed of a fixed cheek made integral with the lower clasp, a movable cheek, and a clamping-screw passing through said cheeks, substantially as set forth.

In testimony that I claim the foregoing as my invention I have signed my name in presence of two subscribing witnesses.

JULIUS HABITZREITER.
